RELIGIOUS DEVICE

Raymond Francis Brennan, Attleboro, Mass.

Application April 27, 1948, Serial No. 23,488

2 Claims. (Cl. 206—19)

1

This invention relates to a composite dual cross structure for ecclesiastical display purposes and consists in improved means for connecting a pair of cross members either in superposed relationship or with one member erected in upright position on the other member.

One object of the invention is to provide a cross structure comprising a base member in the shape of a Latin cross and a second similarly-shaped cross member adapted to overlie said base member in face-to-face relationship or to be erected in upright position on the base member.

Another object is to provide means for slidably connecting the two cross members in contiguous superposed relationship with the upper member forming a tightly fitting cover for an opening or cavity in the base member serving as a receptacle for containing religious articles used for worship and in administering the sacraments of the church.

Another object is to provide telescopically-arranged means for connecting and supporting the upper cross member in upright position on the base member.

Further objects of the invention are set forth in the following specification which describes a preferred form of construction of the cross members and their connecting means as illustrated by the accompanying drawing.

In the drawing:

Fig. 1 is a top plan view showing the two cross members assembled in connected relationship, one superimposed on the other;

Fig. 2 is a perspective view showing the upper cross member erected in upright position on the base member;

Fig. 3 is an enlarged transverse sectional view on line 3—3 of Fig. 1 showing the slidable connection between the upper cross member and the base member;

Fig. 4 is an enlarged plan view of a portion of the base member showing the upper member in fragmentary view as superimposed thereon and illustrating the telescopic connecting means for use in erecting the upper member on the base member as partly telescoped within said upper member; and

Fig. 5 is an enlarged transverse sectional view of the base member showing a portion of the upper cross and illustrating the telescopic connecting means as operative to sustain the upper member in erect position.

Various articles of the present type have heretofore been devised for use by the laity and clergy for purposes of worship and in administering the

sacraments of the church; for example, as a "sick-call," so-called. In most of these prior devices the upper cross member is adapted to be attached in overlying relation to the base member by extraneous means, such as snap fasteners, headed studs and other interlocking devices which project above the base member and are unsightly when the upper cross member is erected in upright position thereon. It is therefore one object of the present invention to provide improved means for connecting the upper cross member with the base member in either overlying or erect position thereon without projections or other obtrusively visible fastening devices on either of the display members of the cross.

Referring to the present drawing, the base member 2 is of the usual shape of a Latin cross comprising a longitudinally-extending body portion 3 with arms 4 and 5 projecting laterally therefrom. The terminal portions of the body member 3 and lateral arms 4 and 5 may be of ornamental contour, for example, carved to form scalloped or fluted ends 6 and 7 as shown in Figs. 1 and 2, for the sake of ornamenting the structure. The body 3 of the base member 2 may be formed with a longitudinally-extending cavity 8 for storing religious articles such as a pair of candles, a container for ointment, a vial for holy water and other ecclesiastical accessories. The opposite arms of the cross may be formed with circular recesses 9 for holding candles 10, indicated by dash lines in Fig. 2.

The upper cross 12 may conform generally to the shape of the base member 2, preferably of thinner section, and being ornamented in any suitable manner with its edges chamfered or rounded as shown at 13 in Fig. 3. The main body 14 of the cross 12 is grooved longitudinally on its sides at 15 to provide splines or runners 16 adapted for engagement with grooves 17 extending along the inner sides of the cavity 8 in the base member 2 and continued therebeyond to the end thereof. As shown in Fig. 3, this interengaging formation of the upper cross 12 and the base member 2 provides a tongue-and-groove connection between the two members when they are placed in superposed relationship by sliding the upper cross along the body 3 of the base member in the manner of closing the cover of a box. Thus, a closely fitting and substantially tight connection is effected between the upper cross 12 and the base member 2 when the upper member is assembled in superposed position on the base member as shown in Figs. 1 and 3. The upper cross 12 thus forms a cover for the recess

or cavity 8 in the base member 2 to retain the religious accessories in the depository of the base member without chance of their escape therefrom.

For supporting the upper cross 12 in upright position on the base member 2 a novel form of telescopic connecting means is provided consisting in a pin 20, see Figs. 4 and 5 of the drawing. The pin 20 is slidably mounted in a bore 21 in the bottom of the body 14 of the upper cross 12 to adapt its end to project therebelow for insertion in a hole 22 in the end of the base member 2. The bore 21 communicates with a substantially circular opening or recess 23 on the rearward side of the cross 12 and a crosspin 24 driven through the upper end of the pin 20 is adapted to engage the lower marginal edge of the recess to prevent the pin from accidental removal from its mounting in the cross.

The telescopic arrangement of the pin 20 adapts it to be slid into the end of the upper cross 12 to house its projecting end when the upper cross is superimposed on the base member 2. Referring to Fig. 4, when the upper cross 12 is slid along the body 3 of the base member 2 with its splines or runners 16 engaged in the grooves 17 the projecting end of the pin 20 will strike the end 25 of the cavity 8 to telescope the pin into the body of the upper cross; thereby concealing the pin from view when the upper member overlies the base member 2 in symmetrical arrangement therewith as shown in Fig. 1.

It will be observed from the foregoing specification and by reference to the accompanying drawing that the connecting means between the upper cross 12 and base member 2 of the dual cross structure are not intrusive either when the upper cross is superimposed on the base member or elevated in upright position thereabove. Consequently, the cross structure has a more ornamental and artistic appearance when its parts are in either arrangement. At the same time, the tongue-and-groove engagement between the base member and the upper cross provides a most simple yet efficient holding means therefor when these members are in superposed relationship, besides serving as a secure closure for the receptacle cavity in the base member. When the cross 12 is erected on the base member 2 the holding pin 20 is almost completely hidden from view and thus all the mechanical parts of the structure are substantially concealed so as to provide a more ornamental and artistic effect to the device as a whole.

It is to be understood that the two cross members may be ornamented in various ways, the upper cross serving as a crucifix if desired, and

other slight modifications may be made in the structure and arrangement of the parts of the device without departing from the spirit of the invention or the scope of the appended claims. Therefore, without limiting myself in this respect, I claim:

1. A composite cross structure comprising a cross-shaped base member having a cavity in its top for containing religious articles, an upper cross adapted to overlie the base member in superimposed relation thereon and cover the cavity therein, means for releasably connecting the upper cross in superimposed relation to the base member, a pin slidable longitudinally in the lower end of the upper cross, means to prevent release of said pin, said pin arranged with its projecting and engageable with the end of the cavity in the base member to cause it to telescope within the upper cross when the latter is placed in superimposed relation on the base member, and a hole in the base member engageable by the projecting end of the pin in the upper cross for supporting the latter in upright position on the lower member.

2. A composite cross structure of the type indicated comprising a cross-shaped base member having a vertical hole at one end, an upper cross adapted to overlie the top of the base member in symmetrical relation thereto, tongue-and-groove formations on the longitudinal sides of the base member and upper cross for slidably connecting the upper cross in superimposed position on the base member, a pin slidable in a longitudinal bore at the lower end of the upper cross, the upper end of said pin being received in a recess in the upper cross when telescoped within its bore, detent means on the pin engageable with the edge of the recess to prevent release of the pin from its bore, and a hole in the base member for receiving the projecting end of the pin when the latter is slid downwardly by gravity whereby to engage the pin with the hole for supporting the upper cross in erect position on the base member.

RAYMOND FRANCIS BRENNAN.
